United States Patent

Des. 237,326
Patented Oct. 28, 1975

237,326

TOOTHBRUSH

Arnold Sims, Beachwood, Ohio, assignor to
Vistron Corporation, Cleveland, Ohio

Filed Apr. 10, 1974, Ser. No. 459,551

Term of patent 14 years

Int. Cl. D4—02

U.S. Cl. D4—25

FIG. 1

FIG. 2

FIG. 3

FIG. 4

FIG. 5

FIG. 1 is a top perspective view of a toothbrush showing my new design;

FIG. 2 is a top plan view;

FIG. 3 is a front elevation of FIG. 2;

FIG. 4 is an oblique elevation taken along line 4—4 of FIG. 3 and looking in the direction of the arrows; and

FIG. 5 is a right-end elevation of FIG. 3.

I claim:

The ornamental design for a toothbrush, as shown and described.
